ELECTRICAL RECEPTACLE COVER

Alfred Robbins, Elmhurst, N.Y., assignor to Perfect-Line Manufacturing Corporation, Hicksville, Long Island, N.Y., a corporation of New York

Filed July 5, 1957, Ser. No. 46,848

Term of patent 14 years

(Cl. D26—13)

Figure 1 is a top plan view of an electric receptacle cover, showing my new design with the lid closed;

Figure 2 is a front elevational view with the lid closed;

Figure 3 is a top plan view with the lid opened; and

Figure 4 is a front elevational view thereof with the lid opened.

The bottom, not shown, has substantially the same appearance as the top shown in Figures 1 and 3, and the back is conventional.

I claim:

The ornamental design for an electric receptacle cover, as shown and described.
